UNITED STATES PATENT OFFICE.

CHRISTOPHER LAUTERBACH, OF BALTIMORE, MARYLAND.

VAPOR-HEATING SYSTEM.

1,151,199.

Specification of Letters Patent. Patented Aug. 24, 1915.

Application filed September 28, 1914. Serial No. 863,823.

To all whom it may concern:

Be it known that I, CHRISTOPHER LAUTERBACH, a citizen of the United States, residing at Baltimore city, State of Maryland, have invented certain new and useful Improvements in Vapor-Heating Systems, of which the following is a specification.

This invention relates to heating systems for dwelling houses, apartment houses and all classes of small and large buildings, and especially to that class of systems known as vapor heating systems, the primary object of the invention being the production and installation of heating systems of this class which shall be of improved construction and operation, requiring but little attention and being as nearly automatic and self-contained as such systems can be made.

With this and other objects in view the invention consists in an improved vapor heating system and the parts thereof, and in the construction, arrangement and combination of such parts, all as hereinafter fully described and afterward specifically claimed.

In order that the construction and operation thereof may be readily comprehended, I have illustrated an approved embodiment of my invention in the accompanying drawings, and will now proceed to specifically describe the construction and operation thereof, having reference to said drawings, in which—

Figure 1 represents in front elevation, a generator forming part of my improved system, connected up to the left of the drawing with a radiator adapted for use in apartment houses and large buildings, and on the right of the drawing, with a radiator adapted for use in private dwellings. Fig. 2 represents in vertical section my automatic air escape valve, parts being shown in elevation and parts broken away. Fig. 3 represents partly in vertical section and partly in elevation, a radiator valve such as I use in radiators in private dwellings and like structures. Fig. 4 represents a transverse sectional view on the construction shown in Fig. 3, taken on the plane indicated by the broken lines 4—4 in said figure. Fig. 5 represents a view, partly in vertical section and partly in elevation, of the radiator valve which I use when my system is applied to apartment houses and other large buildings. Figs. 6 and 7 represent transverse sectional views of the construction

shown in Fig. 5, taken on the plane indicated by the broken line x—x in said Fig. 5, each of said Figs. 6 and 7 illustrating a different adjustment of the valve plugs. 60

Like reference characters indicate the same parts wherever they appear in a plurality of the figures of the drawings.

Referring now in detail to the drawings: A, Fig. 1, designates a vapor or steam generator of any suitable construction and fitted up with all the necessary appurtenances, such as a water supply pipe 1, water column 2, fitted with water gage glass and try cocks, combination pressure and vacuum gage, 3, 70 main vapor supply pipes, 4, riser supply pipes, 5, to radiators, radiator valves, B, C, radiators, 6, of any approved construction, return riser pipes, 7, by-pass pipes, 8, main return pipes, 9, dirt catcher, 10, check valve, 75 11, extension pipe, 12, air pipe, 13, and automatic air escape valve, D. There may be two or more of the automatic air escape valves in the system. The generator, A, is supplied with a smoke collar, 14, in which 80 the main damper, 15, is located. On the outside of the smoke collar, 14, in which a check damper 16 is mounted a suitable pipe is carried to the chimney. The usual draft and ash pit door 17 is also provided. 85

The automatic air escape valve might be of any approved construction but I prefer the construction which forms the subject matter of my U. S. Patent 1,073,354, granted Sept. 16, 1913, and illustrated in detail in 90 Fig. 2 of the drawings of this application. This valve, as fully described in that patent, comprises a bottom casing *a* which is substantially cylindrical and hollow, the lower end being contracted in diameter and externally threaded as at *b* to fit the thread of a pipe or coupling projecting from a radiator, in a well known manner. Near the upper end thereof the casting is provided with a transverse diaphragm *c* in which are ports *d* 100 and the extreme upper end is internally threaded as at *e*, to receive the lower externally threaded end of a hollow cylindrical shell *f*, an upwardly extending lug *g* projecting centrally from the top center of the diaphragm *c*, upon which lug is seated a hollow cylindrical supporting post *h*. Threaded upon the upper externally threaded end of the shell *f* is the top casting *i* which is substantially cylindrical and externally threaded 105 at upper end to receive an internally threaded adjusting cap *j*. This top cast-

ing is provided with a transverse dia-
phragm *i*' having a central threaded open-
ing to receive a hollow exteriorly threaded
adjusting plug *k*. The two ends of the hol-
low adjusting plug *k* are shaped as valve
seats, the lower one to receive and co-act
with the upper conical tip *l* of a hollow bell
float *m* which is supported upon the upper
end of the supporting post *h* and is of a di-
ameter to leave a space *n* in the shell *f*
around said float. The upper valve seat of
the adjusting plug *k* is intended, under cir-
cumstances hereinafter described, to receive
and co-act with the conical lower center *o*
15 of a disk *p*, the conical edge *q* of which co-
acts with a valve seat *r* formed in the upper
end of the top casting *i*, the disk *p*, adapted
to seat on the plug *k* when the plug is ad-
justed to a sufficient height to hold the disk
20 *p* above the valve seat *r*. This disk is pro-
vided in its top center with an upwardly ex-
tending socket *s* to receive a centering screw
t threaded through the center of the top of
the adjusting cap *j*. Port holes *u* extend
25 through the top of the adjusting cap *j*
around the centering screw *t*. The bell float
m and the disk *p* are constructed of brass,
aluminum, or like material, aluminum being
preferable on account of its lightness and
30 anti-oxidizing qualities.

The radiator valves B and C are shown
in detail in the drawings, B being shown in
Figs. 3 and 4 and C in Figs. 5, 6 and 7.

The valve B is provided with a hollow cas-
ing 18 provided with an interiorly threaded
end 19 to fit upon riser pipe 5 and an exter-
iorly threaded pipe end 20 to fit into the
radiator. Fitted in the casing is a hollow
controlling plug 21 having receiving port
35 22 and discharging port 23 which, by turn-
ing the plug, may be made to close or wholly
or partly open the discharging port 23 to
the port 24 of the casing. A packing 25,
gland 26 and packing nut 27 of any ap-
40 proved form and material are provided and
the plug may be set, in any usual manner,
to admit more or less vapor to the radiator.
The radiator valve C, is also provided in a
45 like manner with a hollow casing 18, inter-
iorly threaded end 19 to fit upon the riser
pipe 5, exteriorly threaded pipe end 20 to fit
into the radiator, hollow controlling plug 21
50 having receiving port 22 and discharging
port 23, port 24 in the casing, packing 25,
gland 26 and packing nut 27 all constructed
as in the valve B. The valve C however
55 being intended for apartments and large
buildings, is further provided with a hollow
adjusting plug 28 within the hollow con-
trolling plug 21 and with a suitable packing
60 29 and packing nut 30.

The hollow controlling plugs 21 of both
of the valves B and C, may be set by using
a suitable wrench or other tool upon the
65 projecting ends 31 of such plugs and when

the plug 21 of the valve B is adjusted to
the position shown in Fig. 4 or the plug 21
of valve C adjusted to the position shown in
Fig. 7, the valves are open to their full ca-
pacity.

70 By turning the plug 21 from its wide
open position to any intermediate position
between that and its closed position, as for
instance to the position shown in Fig. 6,
75 the valve may be opened and left open to
any desired extent. In the valve C the ad-
justing plug 28 is carried around with the
controlling plug 21 but when the occupant
80 of the apartment or office room desires to
change the adjustment of the valves, with-
out calling upon the janitor who has pre-
viously set the plug 21 to suit the tempera-
ture, it is only necessary for said occupant
85 to turn the handle 32 of the plug 28 to
carry the plug to any intermediate position,
such for instance as that shown in Fig. 6, by
which means the passage of vapor into the
radiator may be further restricted at will.

This system is designed to work in har-
mony with the well known natural laws, 90
that, heat ascends, cold descends, also, that
the nearer vertical a pipe is, the less friction
it offers to the flow of air, gases, liquids, etc.
For this reason, all supply pipes, including
the main supply pipes, are graded upward 95
from the generator A, to all the radiators,
and the radiator supply pipes are run as
nearly vertical as is possible to the top of
the radiators, where they are connected by
100 radiator valves B or C, or both, to the radi-
ators. The return connections at the bottom
of the radiators (at either end) are open,
that is, either a straight open pipe is used
or a return elbow, either of which offering
105 no obstruction of any kind to the downward
flow of air and water of condensation.

The main return pipes are graded down-
ward from the radiators to the generator A.
This allows a free flow of the air in the radi-
ators and return pipes, and the water of con-
densation, to the air pipe 13, and return pipe
110 9, the air flowing out through the automatic
air escape valve D, and the water of con-
densation down the return pipe 9, through
check valve 11, and extension pipe 12, to
115 the generator A.

The object of the dirt catcher 10, is to
receive all scale and dirt that may be in
the radiators and return pipes, thereby pre-
venting the scale and dirt from passing 120
through and lodging between the disk and
seat of check valve 11, as this check valve
must at all times be tight so as to prevent
the water in generator A, from backing
up in the return pipes. The object of the
125 extension pipe 12, is also to prevent the dirt
which may be in the bottom of the water
leg of generator A, from passing through
and lodging between the disk and seat of
check valve 11.

The by-pass pipes 8 connecting the extended ends of the main supply pipes 4 with the extended ends of the main return pipes 9, are formed into depending water-traps which will receive the water of condensation 5 from the main supply pipes when steam pressure is generated, and will thus prevent the water of condensation from backing up in the ends of the main supply pipes in front of the riser pipes. Under normal 10 conditions, when steam is not being generated, the water in the by-pass pipes or traps offers a resistance to the vapor in the system and prevents its passage to the main return 15 pipes, and when steam is generated, the increased pressure will cause the water in the traps to flow into the main return pipes without causing a resistance to the water of condensation passing from the riser 20 return pipes into the main return pipes. This latter advantage is secured by extending the ends of the main return pipes beyond the risers, so that the water passing from the traps will flow in a direct line with the main 25 return pipes and consequently will not have a tendency to back up in the risers.

The operation of my vapor heating system is as follows: Upon starting a fire in the generator A, as soon as the water in the generator increases in volume from the heat of 30 the fire, that portion of air representing the increase in volume of water, is discharged through the automatic air escape valve D. If the fire be continued until the vapor is 35 generated, there will be a steady discharge of the air in the system through the automatic air escape valve. If now, the fire be drawn from the fire pot of the generator, the vapor in the main supply and riser pipes 40 and in the radiators, if any there be, will condense, the outflow of air through the automatic air escape valve, will cease and the automatic air escape valve will close itself automatically against the inflow of 45 the atmospheric pressure. The combination steam and vacuum gage 3, will show a vacuum, the number of inches of such vacuum depending upon the amount of air discharged from the system. Now however, 50 if instead of drawing the fire from the generator A, the fire be continued until all the radiators and return pipes are hot, then all the air in the system will have passed out through the automatic air escape valve, and 55 a steam pressure will begin to develop, which will be shown by the indicator on the combination pressure and vacuum gage. When this pressure reaches, say, one half pound, the automatic air escape valve D, on account 60 of its internal construction, would prevent any further discharge of steam owing to the steam pressure raising the valve 7 and closing the outlet, thereby allowing the steam pressure in the system to be raised to any desired 65 number of pounds. The raising of a

steam pressure in the system is abnormal, whether by chance or design. Under normal firing and heating conditions, there is only just enough vapor generated within the generator A, and supplied to the radiators, to keep the rooms or house at the desired temperature, usually 70 degrees. This is accomplished by the positive working of the automatic air escape valve D, controlled by the difference between the weight of the 70 vapor generated and the weight of the air in the system. The vapor being lighter than the air, will seek a higher level, and the air being heavier than the vapor, will seek a lower level and all the pipes from the generator to the radiators and from the radiators back again to the generator, are set to facilitate the upward flow of the vapor, and the downward flow of the air in the system. Under normal conditions, if the 75 draft in the smoke chimney is good and anthracite coal used as fuel, the damper 15 in the smoke collar 14, is closed and remains closed, as long as anthracite coal is used, that is throughout the heating season. The 80 draft door 17, remains closed until the outside temperature gets down to freezing and the check damper 16 is set to suit the outside temperatures, said damper 16 having means whereby it can be set to any position from 85 closed to wide open. When the temperature goes below freezing, the check damper 16 is closed and the draft door 17 is opened. Beginning at about one sixteenth of an inch 90 to one quarter of an inch in extremely cold 100 weather, the check damper 16 and the draft door 17, may be set one way for days and weeks, without changing, and all the while the rooms or house are being heated uniformly.

The amount of vapor supplied to the radiators is controlled to a great extent by the gas and air currents in the smoke chimney, and, by the ease with which the air in the system is discharged through the automatic 105 air escape valve, the gas and air currents in the chimney create a slight vacuum in the smoke pipe, increasing and decreasing with the changes in the outside temperature. When the outside temperature lowers, the 110 vacuum within the smoke pipe increases, this will draw a larger volume of air through the cracks around the draft and ash pit doors, or, through the draft door if same is open. This larger volume of air passing up 115 through the bed of burning fuel, generates a larger volume of vapor, this in turn making more of each radiator hot, or if the radiators are hot all over, increasing their heat. If the outside temperature rises, the gas 120 and air currents in the chimney decrease in velocity and the vacuum in the smoke pipe decreases, tending to draw less air through the cracks around the draft and ash pit doors. This smaller volume of air passing 125 130

up through the bed of burning coal generates less vapor, the radiators in consequence giving out less heat, the combination pressure and vacuum gage will show a greater 5 vacuum within the system and the water in the generator A, will boil at a lower temperature, so that, not only is there more or less vapor generated in the generator A automatically, by means of the instantaneous 10 response of the automatic air escape valve to the changes in the velocities of the gases and air currents in the chimney, but the temperature of the water in the generator is also raised or lowered at the same time. 15 This generating of more or less vapor in the generator A, because of the rapid response of the automatic air escape valve to the changes in the velocities of the gas and air currents in the chimney, supplying more 20 or less vapor to the radiators at higher or lower temperatures, means, that in the higher outside temperatures, say sixty five degrees, only the top of the radiators are warm, because the supply connection to the radiators 25 is at the top. As the outside temperature lowers, more of the radiators become hot, from the top downward toward the bottom of the radiators, and only in extremely cold weather when the maximum amount of vapor 30 is generated, are the radiators hot all over.

To have all rooms, or apartments, or building, heated uniformly when only the necessary volume of vapor is generated to suit the outside temperature, the controlling 35 plugs of the radiator valves B and C, are set, closing the outlet ports of the valves more or less, depending upon the closeness of the radiators to the generator A, or the size of the radiators. In addition to this, in 40 apartments, public buildings, etc., radiator valve C, is furnished with the adjusting plug, enabling the occupants of the room or apartments, to either shut off the heat entirely, without in any way interfering with 45 the controlling plug, or to lower the temperature of the rooms, apartments, etc., to any desired temperature below the usually desired 70 degrees.

Since the controlling plugs of the radiator valves B and C are set, so that all the 50 radiators heat equally, it only becomes necessary for the operator of the system to keep the fire pot of the generator A, full of burning coal, and, only change the setting of 55 the check damper and draft door occasion-

ally, to have all the rooms or apartments heated uniformly. In no case is it necessary for the operator to change the setting of the controlling plugs B and C, unless it is desirous of shutting off a radiator entirely, or, lowering the temperature of a particular room or apartment below the temperature agreed upon, usually 70 degrees. 60

While I have illustrated and described 65 specific forms and constructions of valves and other parts comprised in my improved system, I desire it to be understood that my invention is not thus specifically limited. Many slight changes and variations may be 70 made from the construction and arrangement of parts herein described, without departing from the spirit and scope of my invention, as hereinafter claimed.

Having thus fully described my invention 75 what I claim as new and desire to secure by Letters Patent of the United States is

In a vapor-vacuum heating system, a generator, radiators having top and bottom 80 horizontal connections between the vertical coils, supply and return pipes graded upwardly from said generator to the tops of said radiators and downwardly from the bottoms of said radiators to said generator 85 respectively, free open connections between the bottom of said radiators and return pipes, a single air escape means for the system which is connected to said return pipes adjacent the generator, said air escape means 90 being provided with an air vent which is normally closed to the atmosphere and openable by a minimum pressure above atmospheric pressure within the system to maintain normal pressure in the system below atmospheric pressure, and closed against the escape of vapor only by pressure formed with steam generated above 212 degrees F., 95 manual control means in said supply pipes adjacent said radiators for regulating the 100 supply of vapor or steam thereto, and a condensation pipe connected to said return pipes and the bottom of the water-leg of the generator.

In testimony whereof I affix my signature 105 in presence of two witnesses.

CHRISTOPHER LAUTERBACH.
